CLAIM

The ornamental design for projector lens unit for a projector, as shown and described.

DESCRIPTION

FIG. 1 is a perspective view of a projector lens unit for a projector according to an embodiment, viewed from the front side thereof, showing our new design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof; and

FIG. 8 is a reference perspective view showing a usage state thereof.

FIG. 9 is a perspective view of a projector lens unit for a projector according to an embodiment, viewed from the front side thereof, showing our new design;

FIG. 10 is a front view thereof;

FIG. 11 is a rear view thereof;

FIG. 12 is a top view thereof;

FIG. 13 is a bottom view thereof;

FIG. 14 is a right side view thereof;

FIG. 15 is a left side view thereof; and,

FIG. 16 is a reference perspective view showing a usage state thereof.

The article relating to the design of the present application is a projector lens unit for a projector that is connected to a projection section of a projector, to be used. The portion for which a design registration is sought is a mask having no translucency that is attached to a front face of a projector lens for a projector, and the mask having no translucency can be attached to the front face of a transparent projector lens for a projector, to be used. As shown in FIGS. 8 and 16, the present article can be connected to the projection section of the projector, to be used.

The portions represented with solid lines represent claimed portions of the design, the broken lines shown in the figures

(Continued)

are included for the purpose of illustrating portions of the projector lens unit for a projector and form no part of the claimed design.
